UNITED STATES PATENT OFFICE.

JAMES ELLIOTT, OF MONTREAL, QUEBEC, CANADA.

APPARATUS FOR CONSUMING SMOKE IN FURNACES.

SPECIFICATION forming part of Letters Patent No. 293,436, dated February 12, 1884.

Application filed September 6, 1883. (No model.)

To all whom it may concern:

Be it known that I, JAMES ELLIOTT, of the city of Montreal, in the District of Montreal and Province of Quebec, Canada, have 5 invented certain new and useful Improvements in Apparatus for Consuming Smoke in Furnaces; and I do hereby declare that the following is a full, clear, and exact description of the same.

10 This invention has reference to improvements in the art of consuming the smoke which arises from the fires of furnaces, the same being particularly applicable, in whole and in part, to reverberatory furnaces, and some parts 15 to blast and boiler furnaces.

The improvements consist, first, in the introduction of air near the neck or entrance of the flue by means of passages cut through the arch at top and sides, said air being brought 20 from the exterior of the furnace and in a chamber formed outside said arch before being admitted to the smoke chamber or flue; secondly, in the introduction of air above the fire, the same being brought from underneath 25 the grate by passages or flues arranged in the side walls, said passages being joined together in another passage or flue above the fire, and the air forced over the fire by means of a fan or blower; and, thirdly, in the combination, 30 with said air-passages, of steam-jets arranged to discharge over the fire.

For full comprehension, however, of my improvements, reference must be had to the following detailed description, and to the accompanying drawings, in all of which similar letters of reference denote like parts.

In the drawings, Figure 1 represents a plan, partly in section, of a furnace embodying my invention; Fig. 2, a vertical section of same; 40 Fig. 3, a cross-section on line X X, Figs. 1 and 2; Fig. 4, a cross-section on line Y Y, Fig. 2; and Fig. 5, a detail showing arrangement of air-inlets through arch.

A represents the fire-chamber of a reverberatory furnace; a, the grate; B, the ash-pit; c, the bridge; C, the metal chamber or hearth; D, the neck, and E the arch, located just beyond the neck and at the entrance to the chimney or flue F. This arch is formed preferably of brick-

work, the bricks being cut away, as shown in detail in Fig. 5, at intervals, so as to form a series of openings or passages, e e, and outside of this arch a hood, G, of brick or metal, is placed in such manner that a space or chamber, g, will be formed between them, into which air from the exterior of the furnace can flow through a suitable opening, g', controlled by a damper, g''. The air is heated in passing through this chamber g, and is drawn downward through the passages e e by the draft of furnace into 60 the neck or base of the flue leading to the chimney.

At the front or side of the chamber A, toward its crown and at right angles to the line of draft, I construct in the brick-work or otherwise, as may be found desirable, a passage or flue, H, provided with a suitable number of openings, h h, on that side which projects toward the bridge-wall c; or this side of the flue may have a long opening, if preferred. I 65 also construct in the side walls of the furnace vertical flues J J, opening into the ash-pit at their lower ends, and forming a junction with the flue H; at each end of same, as seen in Figs. 1, 2, and 3.

Along the side of the fire-chamber, and running in the same direction as the grate-bars and flue H, I sometimes arrange a steam-pipe, K, having any suitable number of nozzles, k, projecting into said flue H, steam being supplied to this pipe from a separate boiler, if such steam-jets are required, in furnaces which do not raise steam.

The dotted lines at L represent any ordinary blower or fan, and l the pipe leading from same to a point underneath the grate, as is customary in blast or other furnaces requiring an additional supply of air for draft and for aiding combustion.

In operating my invention steam-jets will 90 not be required in all cases, as I chiefly rely on the blower or fan L to force the air (which is warmed first in the side flues, J J,) out upon the fire from the flue H, such additional 95 supply of air, as is well known, aiding the combustion of the light carbon and gases arising from the fire.

Heretofore, to the best of my knowledge, a blower has only been used to act on the fire by forcing a current of air from underneath up between the grate-bars. By my invention 5 I utilize the force of the blower to project currents of air through my vertical flues into the transverse flue, and thus over the fire, which I have found gives much better results than when introduced as first mentioned. Of course 10 steam-jets will greatly assist in the introduction of this air above the fire, and the hydrogen of the steam will also form a valuable addition in the consumption of the smoke, as I have explained in my previous patents, and as 15 is well known to engineers. It will be seen, also, that by introducing an additional volume of air at the neck of a furnace such as is shown in the drawings, I cause whatever particles of carbon and the gases which may es- 20 cape over the bridge-wall to be ignited and consumed before reaching the chimney.

I am aware that it is not novel, broadly speaking, to introduce bodies of air to different parts of furnace-chambers, nor to use steam-jets for forcing air over the fire, nor yet to use 25 a fan-blast directed underneath the grate-bars.

I am aware that it is not new to introduce air at the neck or base of flues in furnaces of this

class, and I do not broadly claim such as my invention; nor do I claim, broadly, the introduction of air to the fire-chamber above the grate by means of flues and passages in the walls of the furnace leading from the ash-pit, my invention being limited to the arrangement particularly described; but 30

What I claim, and desire to secure by Letters Patent, is as follows:

1. For introduction of air to the fire-chamber above the grate, vertical flues J J, formed in the side walls, and opening at their lower 40 ends into the ash-pit, and joined at their upper ends to a flue, H, formed at the crown of said fire-chamber, at right angles to the line of draft, and having openings h h, and a blower or fan for forcing said air through said flues 45 and over the fire, substantially as and for the purpose described.

2. In a furnace, the combination, with flues J J and H, of the steam-pipe K, having nozzles k k, and a fan or blower, L, substantially 50 as and for the purpose specified.

JAMES ELLIOTT.
